US00D683704S

(12) **United States Design Patent**
Egan et al.

(10) **Patent No.:** **US D683,704 S**
(45) **Date of Patent:** **** Jun. 4, 2013**

(54) **WALL-MOUNTED DIGITAL TERMINAL ADAPTER**

(75) Inventors: **Chris Egan**, Parker, CO (US); **Brent Robert Smith**, North Vancouver (CA); **Tom Lambrecht**, Parker, CO (US); **Perfecto D. Martinez**, Castle Rock, CO (US); **Kee Cheol Lee**, Gyeonggi-Do (KR); **Jong Woong Park**, Seoul (KR)

(73) Assignee: **Evolution Digital, LLC**, Centennial, CO (US)

(**) Term: **14 Years**

(21) Appl. No.: **29/405,146**

(22) Filed: **Oct. 28, 2011**

(51) LOC (9) Cl. **13-03**

(52) U.S. Cl.

USPC **D13/151**

(58) **Field of Classification Search**

USPC D13/133, 146, 147, 151, 154, 158, D13/184, 199; D14/125, 217, 230, 239, 299; 174/59; 333/100, 101, 206; 439/63, 579, 439/578, 581, 709

(57) **CLAIM**

The ornamental design for a wall-mounted digital terminal adapter, shown and described.

DESCRIPTION

FIG. 1 is a perspective view of the wall-mounted digital terminal adapter showing our new design from the front, bottom and left sides;

FIG. 2 is a perspective view thereof showing our new design from the rear, bottom and right sides;

FIG. 3 is a front side elevational view thereof;

FIG. 4 is a rear side elevational view thereof;

FIG. 5 is a top side plan view thereof;

FIG. 6 is a bottom side plan view thereof;

FIG. 7 is a right side elevational view thereof; and,

FIG. 8 is a left side elevational view thereof.
